UNITED STATES PATENT OFFICE.

WILLIAM HERBERT ROYSTONE, OF NEW YORK, N. Y.

TOILET ARTICLE.

1,388,204.

Specification of Letters Patent. Patented Aug. 23, 1921.

Application filed August 7, 1920. Serial No. 402,003.

To all whom it may concern:

Be it known that I, WILLIAM HERBERT ROYSTONE, a citizen of the United States, residing at New York city, county and State 5 of New York, have invented a new and useful Improvement in Toilet Articles, of which the following is a specification.

This invention relates to toilet articles and more particularly to the provision of an 10 proved packet of toilet powder such as face powder, nail powder, rouge or the like.

The invention seeks to provide a packet of toilet powder in which the powder shall be so confined as to prevent waste of the substance 15 while in use, and obviate untidiness incident to such waste, and that shall preserve the mass at all times in a neat and satisfactory condition while permitting the powder to be freely dispensed by the user. 20 Heretofore, these powders have been put up in packages in which the powder is either in loose form in its container or is in the form of an uncovered or unconfined compact or cake. Where the powder is put up 25 in loose form, the applicator by which it is applied, such for example, as a powder puff, picks up from the mass an excess of the powder and makes it generally impossible to use such loose powder without waste or 30 without an untidy spilling of the powder. If the package should be dropped, much waste of the powder and general untidiness result. Where the powder is put up in the form of a compact or cake, the cake frequently 35 breaks or crumbles before it reaches the user, and so becomes unsalable. And if it reaches the user intact, it frequently breaks and crumbles while in use, thereby becoming unsatisfactory and difficult to use 40 and likely to spill from its container and so causing waste and untidiness. These disadvantages are overcome in my improved packet wherein the powder is compressed and is covered by a pervious fabric suffi- 45 ciently loose to permit the fabric to be slightly moved over the surface of the compressed mass by rubbing the fabric covering, as by means of a powder puff or other suitable applicator.

50 The accompanying drawings show one method of making my improved packet and also the packet.

Figure 1 illustrates the elements which generally go to make up a packet of face powder and a mold useful in making the packet.

Fig. 2 illustrates the parts assembled in the mold.

Fig. 3 illustrates a finished packet of the powder. 60

Fig. 4 illustrates a vanity box containing my improved packet.

Referring now to the drawings, 10 is the powder. It may, if desired, be in the form of a substantially flat compact of a size and 65 shape adapted to fit into the mold 13. 11 is a piece of pervious textile fabric, generally thin cotton cloth, of suitable size. It is placed over the mold and the powder 10 is then pressed into the mold with the fabric 70 11 covering the interior of the mold. A disk of cardboard, tin or other suitable thin, sheet material is then applied to the upper surface of the mass and the edges of the cloth are brought over the upper margin of 75 the disk and fastened in place, as by an adhesive. The packet as thus assembled is then removed from the mold 13 and reduced in size. This is preferably done by compressing the packet into a second and 80 slightly smaller mold. This reduction in the size of the compressed mass of powder slightly loosens the cloth covering 11 and makes it slightly movable over the face of the compressed mass so that when it is 85 moved, as by rubbing an applicator over the cloth covering, the covering slightly abrades the surface of the compressed mass and loosens a small amount of the powder which passes through the cloth and on to 90 the applicator. The packet A, as thus completed, is shown in Fig. 3.

In marketing the powder as a face powder or rouge, the packet A is generally removably fitted into a vanity box 15 having a bottom 14 and a cover 17, and the box is of such depth as to permit of a puff or applicator 16 being inclosed beneath the cover 17. 95

It will be seen that the compressed powder remains permanently inclosed in its cloth 100 covering which acts to protect the compact and tends to prevent it from breaking either in shipment or in use. Even though the compact should become broken, the cloth covering 11 serves to maintain the powder 105 in substantially its original form and in salable and usable condition and prevents the escape of the powder.

It is preferable to apply the powder by means of an applicator, such as the powder 110 puff 16. The applicator is rubbed over the surface of the covering 11 to obtain its sup-

2

ply of the powder. In this action the covering is made to move slightly over the surface of the compressed powder to slightly abrade the same and detach a small quantity of the powder, which then passes through the meshes of the covering and on to the applicator. The powder is thus freely supplied to the applicator but in a limited amount so that waste and spilling thereof is prevented. And the applicator picks up little, if any, more powder than is actually required for immediate use.

Various procedures may be followed in making the packet and in making it so that the cloth covering has the required looseness and I do not desire to be restricted to the particular procedure that I have described for making it nor to all the details of structure herein described.

20 20 What is claimed is:

1. A toilet powder packet comprising a compressed mass of toilet powder having a covering of pervious fabric sufficiently loose to admit of its being moved over the surface 25 of the inclosed mass by rubbing.
2. A toilet powder packet comprising a cake of toilet powder, a backing of stiff, sheet material for one face of the cake and a covering of pervious fabric for the remainder 30 of the cake fastened to said backing, said covering being capable of movement over the surface of the cake to abrade its surface and detach a quantity of the powder.
3. The process of making a toilet powder 35 packet which consists in pressing a quantity of the powder into a mold with a pervious fabric interposed between the mold and the powder, fastening the fabric as a covering about the compressed powder, then reducing

the size of the inclosed mass of powder to 40 render the cover relatively loose, for the purpose set forth.

4. The process of making a toilet powder packet which consists in pressing a quantity of the powder into a mold with a pervious 45 fabric interposed between the mold and the powder, applying a backing of stiff sheet material to the upper face of the powder, fastening the fabric to the backing as a covering for the compressed powder, then reducing 50 the size of the inclosed mass of powder to render the cover relatively loose, for the purpose set forth.

5. A toilet article comprising a compressed cake of face powder, rouge or the like, a 55 backing of sheet material for one face of the cake and a covering of porous fabric for the remainder of the surface of the cake fastened to the backing by an adhesive, said covering being sufficiently loose so that it 60 may be moved by a powder puff.

6. A toilet article comprising a compressed cake of face powder, rouge or the like and a covering of porous fabric, said fabric being sufficiently loose so that it may be moved 65 over the surface of the cake by a powder puff.

7. The combination with a substantially flat mass of compressed face powder, rouge or the like, of a loose fabric covering therefor, which covering permits a small amount of the powder to pass through the same only when rubbed as by a powder puff or the like, said covering further retaining the unsifted material in serviceable form or condition.
